UNITED STATES PATENT OFFICE.

FRITZ O. VON TOBEL, OF OMAHA, NEBRASKA.

DESIGN FOR A COMBINATION-TOOL.

53,260.

Specification for Design.

Patented Apr. 29, 1919.

Application filed December 29, 1915. Serial No. 69,293. Term of patent 14 years.

To all whom it may concern:

Be it known that I, FRITZ O. VON TOBEL, a citizen of Switzerland, residing at Omaha, in the county of Douglas and State of Nebraska, have invented a new, original, and ornamental Design for Combination-Tools, of which the following is a specification, reference being had to the accompanying drawing, forming part thereof.

Figure 1 is a view of the obverse side of the design.

Fig. 2 is a view of the reverse side of the design, and

Fig. 3 is a top plan view thereof.

I claim:

The ornamental design for a combination tool, as shown.

FRITZ O. VON TOBEL.
